TOY BASEBALL GAME DEVICE

George Geller, Yonkers, N. Y.

Application May 3, 1949, Serial No. 91,129

11 Claims. (CL 273—89)

1

The present invention relates to toys, and, in particular to a toy with which a simulated game of baseball may be played by two or more people.

The general object of the invention is to provide a new, simple, and inexpensive toy baseball game device with which two or more people may join in a contest of skill approximating an actual game of baseball.

The invention contemplates apparatus by means of which one player can "pitch" an actual ball through the air and over a home plate at not less than a predetermined height thereabove; means for "catching" pitched balls passing beyond home plate so as to indicate a "strike" or "ball" in accordance with the trajectory of the pitched ball with respect to the home plate similarly as such pitched balls are scored in the actual game of baseball; other apparatus in simulation of a batter standing proximate to home plate, said other apparatus comprising a manikin holding a miniature bat and means associated with said manikin whereby the same may be caused to swing the bat into the path of an oncoming pitched ball with a speed and timing determined by the reflexes of a second player; and a simulated baseball field having traps thereon to arrest batted balls at particular stations to indicate as of each station a given score relating to the game of baseball.

The invention contemplates a toy baseball game device adapted to be played with skill comparable to that commonly required by actual baseball players. One player serves as pitcher, another as batter, and a third may well serve as umpire. The game device is such that superior skill on the part of the pitcher or batter, as the case may be, actually operates to determine the outcome of the game, which may be played strictly in accordance with the well known rules of baseball.

A special object of the invention is to provide novel apparatus in a toy baseball game device adapted to make possible the use of skill on the part of the player serving as pitcher and to catch a pitched ball passing unhit beyond the home plate in such manner that the scoring of the pitch is indicated by the catch itself, the ball being pitched by attaching the same to a magnetic pendulum held out of plumb, and the catch being scored in accordance with the position of rest assumed by said pendulum against a paramagnetic backboard situated beyond home plate.

A further special object of the invention is to provide improved means for actuating a manikin batter whereby the player serving as batter may

2

easily and rapidly effect batting operation of the manikin in accordance with the player's reflexes on observing the approaching ball.

A further object of the invention is to provide 5 a paramagnetic playing ball adapted to adhere to a magnetic pendulum of predetermined length whereby, in a pitch, the ball is prevented from passing over or near home plate at less than a predetermined height thereabove.

10 A further object of the invention is to provide a novel toy baseball game device having a diamond suitably marked upon its field and being provided with a number of playing pieces which may be variously positioned from time to 15 time as the play progresses so that a cumulative visual record of the progress of play is available to the players.

These and other objects of the invention will 20 be apparent from the following description and from the drawing in which—

Fig. 1 is a plan view of the device;

Fig. 2 is a front elevational view thereof, partly erased to condense the figure, and partly broken away in front to show interior features;

25 Fig. 3 is an enlarged, fragmentary vertical section in accordance with the index 3—3 of Fig. 1;

Fig. 4 is a longitudinal sectional view of the device in accordance with the index 4—4 of Fig. 1;

Fig. 5 is an enlarged, fragmentary sectional detail showing an edge elevational view of the backstop;

Fig. 6 is an enlarged, fragmentary sectional detail showing a front elevational view of the backstop; and

35 Fig. 7 is an enlarged, fragmentary sectional detail in accordance with the index 7—7 of Fig. 1.

The base 1 of the device is a shallow box having, preferably, a laminated bottom comprising a relatively thick upper sheet 2 superimposed on a relatively thin lower sheet 3 (see Figs. 3, 4, 5, 6, and 7), the upper surface of the sheet 2 constituting a miniature playing field having appropriately marked thereon a diamond 4, a home plate 5, first, second, and third bases 6, 7, and 8, respectively, and foul lines 9, 9. See Fig. 1. A scoreboard 10 may also be marked upon said surface at a convenient place behind the diamond, as shown. The walls of the box, designated in their entirety, 11, serve both as means for safely enclosing removable parts of the device when the same is disassembled in part for packaging and shipment or storage, and as means for preventing a ground or grounded ball from rolling off the field. It will be understood, of course, 50 that the walls 11 may also be regarded as repre-

senting the fence of a ball park, and a batted ball fairly clearing the walls may be called a home run after the usual custom.

The upper sheet 2 is fenestrated within the fairway near the walls 11 to provide, in the right, back, and left fields, a plurality of pits (the bottom of each being the sheet 3; see, particularly, Fig. 3) into which a ground or grounded ball may, under certain circumstances, roll and come to rest so as to indicate by its presence a certain score according to a label, not shown, marked on the bottom of the pit.

For example, here, in the illustrated embodiment, five such pits, 12-16, inclusive, are provided in the right field; five similar pits, 17-21, inclusive, are provided in the left field; and eight other pits, 22-29, inclusive, are provided in the back field.

These pits may be labeled in any suitable manner with scoring indicia. The following scheme is suggested, although no labels are entered in the drawing: 12, three base hit; 13, fly out; 14, two base hit; 15, fly out; 16, home run; 17, two base hit; 18, double play; 19, three base hit; 20, fly out; 21, home run; 22, double play; 23, two base hit; 24, fly out; 25, one base hit, base runner advances two bases; 26, home run; 27, fly out; 28, two base hit; and 29, sacrifice fly, runner scores from third.

Mounted on the sheet 2 within the fairway are a plurality of traps adapted to catch and arrest, under certain circumstances, a ground or grounded ball. These traps are of a common construction, each preferably comprising a pair of nearly rectangular wickets, each wicket having relatively short legs sunk into or otherwise suitably mounted on sheet 2 and a relatively long horizontal bridge; see Figs. 1, 2, 4, and 7. The wickets of any pair are relatively positioned so as to form a V through the bottom of which a ball may not pass. Obviously, of course, the height of the bridge of any wicket is such as to deflect and detain within the related trap a moderately slow ground or grounded ball entering the same, although it will be understood that such a ball entering the trap with considerable speed might well bounce out of the trap in one of a variety of possible manners and enter another trap and proceed into one of the pits.

The traps here shown are seven in number to accord with the field players of a baseball game. Trap 30 is near first base; traps 31 and 32 in shortstop positions; trap 33 near third base; and traps 34, 35, and 36 in the field farther out from the batter. A batted ball coming to rest within any trap may be regarded as having been caught and therefore represents a fly out.

If desired, a batted ball which contacts a trap and is not arrested thereby, and so escapes, may be called an error so as to advance all men on base.

The pitcher's mound on sheet 2 is designated 37.

Behind home plate, in line with the plate and the pitcher's mound, is a post 38, the lower portion of which is inserted into a socket 39 provided in the rear portion of the walls 11 (see Figs. 1, 2, 4, 5, and 6).

A cantilever 40 is secured to the top portion of the post 38 and extends forwardly slightly beyond the center of the home plate 5. See Fig. 4, particularly; also Figs. 1 and 2.

Suspended from the cantilever 40 is a filament 41, which may well be a string, threaded through an eyelet 42 in the forward portion of the canti-

lever and secured thereto in any suitable manner, as by knotting. At the lower end of the filament 41 is secured a permanent magnet 43, preferably a simple bar. Normally the magnet 43 hangs just over the center of the home plate 5 and at a predetermined height above the home plate (see below).

Standing before the post 38 is a paramagnetic shield, or back stop, 44, which may be shaped substantially as shown in the drawing. An enlarged view of the left side and front of the shield 44 is provided by Figs. 5 and 6.

The shield 44 is preferably a rectangular sheet of steel bent on the top and bottom to provide two flanges at 90° to the general body of the sheet. The lower bent portion 45 is secured in any suitable manner to the upper sheet 2 (see Fig. 5); the upper bent portion 46 is preferably provided with an aperture at 47 through which post 38 may be freely passed. See Figs. 5 and 6.

A target 48 is shown to be marked on the front surface of the shield 44 in Figs. 2 and 6. In the enlarged view, Fig. 6, the target is shown to be marked with the word Strike. The position of the target roughly approximates zone within which a catcher would normally receive a strike. That portion of shield 44 surrounding the target represents the zone within which a catcher would normally receive a ball, so-called in accordance with the rules of baseball.

The device is provided with a manikin batter 49. The manikin may be variously constructed within the scope of the invention, but the preferred construction is as follows:

The manikin is made in two parts pivotally connected at or about the waistline 50. The upper portion of the manikin is designated 51, the lower portion 52. The lower portion 52 of the manikin is rigidly secured to sheet 2 just to the left of home plate 5 (i. e., the batter, here, is assumed to be righthanded). The upper portion 51 of the manikin is mounted on the fixed lower portion 52 in any suitable manner which adapts said upper portion to be freely rotated upon said lower portion on a vertical axis.

The manikin's arms are rigidly secured to the upper portion 51 and also to a miniature bat 53. Thus when the upper portion 51 is rotated the bat is moved in simulation of a swing parallel to sheet 2. The height of the bat 53 is such that if it is swung while the magnet 43 is hanging at rest over home plate the bat passes immediately beneath the magnet.

Any suitable means may be provided whereby the upper portion 51 of the manikin can be actuated. Preferably such means are a sheathed flexible cable 54 of the type well known in photographic arts as a means for triggering a shutter. The outer end of the cable is supplied in the usual manner with a finger button 55, and the inner end of the cable is passed through an aperture 56 of the lower portion 52 of the manikin and is attached in suitable manner eccentrically to the bottom of the upper portion 51 of the manikin. Of course the cable may be provided in the usual manner with a compression spring within the sheath 57, or within the manikin, as desired. It will be understood, of course, that when the finger button 55 is pressed the cable 54 moves axially within its sheath 57 and transmits pressure exerted on the finger button to the upper portion 51 of the manikin, causing the same to rotate and thereby swing the bat. Speed with which the manikin simulates the batting operation of course relates to the speed with which the finger button

is pressed; and the apparent timing of the batter with respect to pitched balls is, in fact, the timing of the player operating the finger button.

The playing ball is preferably of steel, such as a bearing ball, and is approximately scaled to accord with the manikin and bat. The ball, wherever shown or indicated in the drawing, is designated B. The ball is required to be paramagnetic, whatever its material may be; and when placed in contact with the permanent magnet 43 near the lower pole thereof automatically positions itself on the bottom of the magnet as shown in Figs. 2 and 4, this position being that which most nearly represents the mean of the force of attraction of the lower pole of the magnet and of gravity.

If, after the ball has been placed against the lower pole of the magnet, the string or filament 41 is gently allowed to assume a natural position of repose, the relationship of the manikin, bat, ball, and magnet will be as illustrated in solid lines in Fig. 4. Cf., also, Fig. 1, the plan view, and Fig. 2, the front elevational view.

The player serving as the pitcher may swing the magnet and ball forwardly and upwardly, with the filament substantially taut, to a position such as is represented by dotted lines in Fig. 4; and, when the magnet and ball are so positioned—presumably over the pitcher's mound—the two elements may be released to effect the pitch. The filament, magnet, and ball operate together as a pendulum, and, accordingly with the amount of bias induced by the player serving as pitcher, swings over the home plate or to the right or left. The ball, if the pendulum swings directly over the home plate, is carried thereover at the height above sheet 2 equal to the corresponding height of the manikin's bat.

The player serving as batter may swing the upper portion of the manikin, and, of course, the bat together therewith, at such speed and at such time as his vision, dexterity, and sense of timing make possible for him, in an attempt to strike the oncoming ball. If the bat of the manikin strikes the ball more or less squarely the ball is almost invariably knocked off the magnet. Its trajectory thereafter and its final destination are naturally governed by physical factors equal to nearly all actually present in the striking of a pitched ball by a human player. A factor not present here, however, is that relating to a moment tending to propel the ball definitely downward (without respect to the additional pull of gravity) or upward, as the manikin's bat invariably swings in a horizontal plane, and the player serving as batter has no means for changing the plane of the swing. For the purposes of a gaming device of this kind which must necessarily be small it is obviously desirable to eliminate means for changing the batting plane in order to prevent too erratic behavior of the struck ball with respect to the miniature playing field.

If the player serving as batter judges the oncoming ball to have been released by the pitching player in such manner that the ball will not pass over the home plate, the batting player may advisedly not attempt to strike the ball at all. The paramagnetic backstop 44 with its target 48 serves as a sort of umpire. If the batting player does not strike at the oncoming pitch, and the magnet strikes and adheres to the backstop out of the area of the target 48, the pitch may be called a ball; but if the batter fails to swing and the magnet comes to rest within the target area, where the word Strike is lettered, a strike may be charged against the batter. Likewise, where the

batter swings and misses, a strike may be charged against him or not, according to such rules as the players may make up among themselves relating to the position of rest finally assumed by the magnet.

If a pitched ball is struck by the bat it normally travels forwardly to the field (trajectory a, Figs. 1 and 4), where it may or may not come to rest within one of the traps 30—36, inclusive, or to the fence (trajectory b, same figures), where it may or may not come to rest within one of the pits 12—29, inclusive, or over and beyond the wall 11 of the gaming device (as indicated by trajectory c, same figures, in which all trajectories are indicated in dotted lines).

A ball is shown arrested within a trap in Figs. 1, 2, 4, and 7; entering (dotted lines) and arrested within (solid lines) a pit (pit 21; cf. Fig. 1) in Fig. 3, also arrested within a pit in Figs. 1, 4, and 7. The traps, as mentioned above, represent playing men of a baseball team; the pits may be marked to score in any fashion desired.

The game is preferably provided with a plurality of markers M (see Fig. 1 where one is shown on second base 17), which may be small disks of wood or other suitable material, whereby a sort of cumulative visual record of the stage of play may be kept by the players.

Also, the scoreboard 10 may be suitably surfaced to take chalk or other marks, for facilitating score keeping.

I claim:

1. In a toy baseball game, a home plate marker, a bat, mechanism for swinging said bat in a path passing over said marker, a magnet suspended for pendulous movement and normally hanging at rest over said marker and above said path, and a paramagnetic ball adapted to be suspended from said magnet and to be carried thereby during pendulous movement thereof to intersect said path whereby said ball may be served across said marker for dislodgment from said magnet by said bat.

2. In a toy baseball game, a home plate marker, a manikin holding a bat and adapted to be manually actuated to swing said bat in a path passing over said marker, a magnet suspended for pendulous movement and normally hanging at rest over said marker and above said path, and a paramagnetic ball adapted to be suspended from said magnet and to be carried thereby during pendulous movement thereof to intersect said path whereby said ball may be served across said marker for dislodgment from said magnet by said bat.

3. In a toy baseball game, a base marked to represent a baseball diamond and including a home plate marker, a plurality of traps on said base representing various players opposing a batter, another plurality of traps on said base representing various hits of the game of baseball, a bat, mechanism for swinging said bat in a path passing over said home plate marker, a magnet suspended for pendulous movement and normally hanging at rest over said home plate marker and above said path, and a paramagnetic ball adapted to be suspended from said magnet and to be carried thereby during pendulous movement thereof to intersect said path whereby said ball may be served across said home plate marker for dislodgment from said magnet toward one of said traps by said bat.

4. In a toy baseball game, a home plate marker, a bat, mechanism for swinging said bat in a path passing over said marker, a magnet suspended for

pendulous movement and normally hanging at rest over said marker and above said path, a paramagnetic ball adapted to be suspended from said magnet and to be carried thereby during pendulous movement thereof to intersect said path whereby said ball may be served across said marker for dislodgment from said magnet by said bat; and a paramagnetic back stop behind said marker adapted to arrest pendulous movement of said magnet.

5. In a toy baseball game, a home plate marker, a manikin holding a bat and adapted to be manually actuated to swing said bat in a path passing over said marker, a magnet suspended for pendulous movement and normally hanging at rest over said marker and above said path, a paramagnetic ball adapted to be suspended from said magnet and to be carried thereby during pendulous movement thereof to intersect said path whereby said ball may be served across said marker for dislodgment by said bat, and a paramagnetic back stop behind said marker adapted to arrest pendulous movement of said magnet.

6. In a toy baseball game, a base marked to represent a baseball diamond and including a home plate marker, a plurality of traps on said base representing various players opposing a batter, another plurality of traps on said base representing various hits of the game of baseball; a bat, mechanism for swinging said bat in a path passing over said home plate marker, a magnet suspended for pendulous movement and normally hanging at rest over said home plate marker and above said path, a paramagnetic ball adapted to be suspended from said magnet and to be carried thereby during pendulous movement thereof to intersect said path whereby said ball may be served across said home plate marker for dislodgment from said magnet.

lodgment from said magnet toward one of said traps by said bat; and a paramagnetic back stop behind said home plate marker adapted to arrest pendulous movement of said magnet.

7. The combination of claim 3 wherein said mechanism includes a manikin representing a batter.

8. The combination of claim 6 wherein said mechanism includes a manikin representing a batter.

9. The combination of claim 4, including a pitcher's mound marker, and a target marked on said back stop in alignment with said pitcher's mound marker and said home plate marker.

10. The combination of claim 5, including a pitcher's mound marker, and a target marked on said back stop in alignment with said pitcher's mound marker and said home plate marker.

11. The combination of claim 6, including a pitcher's mound marker, and a target marked on said back stop in alignment with said pitcher's mound marker and said home plate marker.

GEORGE GELLER.
